UNITED STATES PATENT OFFICE.

HENRY M. BASCOM, OF BROOKLYN, NEW YORK, ASSIGNOR TO AMERICAN TELEPHONE AND TELEGRAPH COMPANY, A CORPORATION OF NEW YORK.

MEASURING SYSTEM.

Application filed August 10, 1927. Serial No. 212,099

This invention relates to telephone systems in which it is desired to meter the service by recording the length of time the subscriber's telephone is in use.

in series with the leads and a large capacity 16 connected across the leads. A more elaborate filtering arrangement may be provided, if desired, but these elements constitute in effect a low-pass filter which serves to prevent all frequencies above a limit of say 40 cycles per second, which are incident to the sudden opening and closing of the reversing switch, from getting on to the talking conductors of the connection. The capacity 16 may conveniently be of the electrolytic type giving a large capacity in a small compass.

5 In such systems, it has been proposed to operate a metering device periodically by reversing the polarity of the source of energy used for the talking connection. It is the object of the present invention to provide a 10 simple and inexpensive mechanism for reversing the current in such a system, and to this end to provide a simple reversing switch and filter elements for preventing the line from picking up noise due to the com- 15 paratively sudden make and break of the reversing switch.

As above pointed out, the reversing mechanism is shown on one side of the cord circuit only, since, in general, it is desirable to charge the call to the calling subscriber only. It will be obvious, however, that the same mechanism could be applied on both sides of the cord circuit, if desired. The reversing switch and filter elements, which are shown to the left of the dotted line 16, may be common to all of the cords of a given exchange, or to a group of cords, or, of course, if desired, may be supplied for each cord separately. 65 70 75 75

While I have illustrated the invention in connection with a typical cord circuit used in manual operation, it will be evident that the invention is equally applicable to machine switching apparatus. 80

What is claimed is:

1. In a telephone system, a central office, subscribers' stations adapted to be connected thereto, polarized metering apparatus located at the subscribers' stations, connecting circuits and a source of direct current energy at the central office, a switch for reversing the connections of said current source to one end of the connecting circuits at regular intervals at a frequency below audibility, choke coils located in the leads between said reversing switch and said connecting circuits, and a capacity connected across said leads adjacent said choke coils. 95

2. In a telephone system, a central office, subscribers' stations adapted to be connected thereto, connecting circuits at said central office, polarized metering apparatus adapted to register the period of use of the subscrib- 100

ers' stations, a source of direct current energy, a switch for reversing the connections of said source to one end of the connecting circuits at intervals of a frequency below audibility, and devices connected between said reversing switch and said connecting circuits for preventing disturbances due to said re-

versing switch from reaching said connecting circuits.

In testimony whereof, I have signed my name to this specification this 4th day of August 1927.

HENRY M. BASCOM.
